(57) **CLAIM**

The ornamental design for a toy rocket, as shown and described.

DESCRIPTION

FIG. 1 is a front view of a toy rocket showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view of the toy rocket thereof; and, FIG. 8 is a perspective view of the toy rocket shown in an alternative configuration of use.

The broken lines shown in the drawings illustrate portions of the toy rocket that form no part of the claimed design.
